UNITED STATES PATENT OFFICE.

WILLIAM H. HARFIELD, OF LONDON, ENGLAND.

IMPROVED APPARATUS FOR WORKING AND STOPPERING CHAIN CABLES.

Specification forming part of Letters Patent No. 36,085, dated August 5, 1862.

To all whom it may concern:

Be it known that I, WILLIAM HORATIO HARFIELD, of No. 2 Royal Exchange Buildings, in the city of London and United Kingdom of Great Britain, have invented a new and Improved Apparatus for Working and Stoppering Chain Cables; and I do hereby declare that the following is a full and exact description thereof, reference being had to the accompanying drawings, which form a part of this specification.

This invention consists, first, in a peculiar arrangement of such means as enables me to use, in connection with a windlass, the chain-carrier or "flanged annular recess" which was patented by Thomas Brown in Great Britain, April 20, 1847, and in the United States July 25, 1854; and, second, said invention consists in such an arrangement of the respective parts of my improved chain-carrying windlass that it can be used in connection with the "underlifting stopper," which was also secured in the aforesaid patent of Thomas Brown.

Figure 1 is a plan of my improved apparatus for working and stoppering chain cables; Fig. 2, a back view; Fig. 3, an end view; Fig. 4, a section in the line $y-y$ of Fig. 2; Fig. 5, a section in the line $x-x$ of Fig. 2; Fig. 6, a section in the line $z-z$ of Fig. 1; and Figs. 7 and 8 are sections in the line $a-a'$ of Fig. 1.

Similar letters indicate the same parts in all the drawings.

The journals near the ends of the windlass-shaft F are received into suitable journal-boxes that are secured to the strong supporters $E E$, while the central journal of said shaft is received into a box that is secured to the central supporter, H .

A strong ratchet-wheel, D , is rigidly secured to the windlass-shaft F on each side of the central supporter, H , and the portions of said shaft between the ratchet-wheels and the end-supporters $E E$ of the same receive the chain-carriers $C C$, the said chain-carriers being allowed to play loosely upon the windlass-shaft, save when they are coupled to the ratchet-wheels $D D$ by the catches $g g$. The catches $g g$ are short rectangular bars that are received into radial recesses formed in the outer faces of the ratchet-wheels D . The said bars are also jointed at their inner ends, while

their outer ends project beyond the peripheries of the ratchet-wheels and the chain-carriers. Radial grooves are also formed in the inner faces of the chain-carriers, the width of which is such that they will freely receive the catches $g g$ when they are brought opposite the same. Consequently, it will be perceived that the chain-carriers can be securely coupled to or disconnected from the ratchet-wheels by simply changing the positions of the catches $g g$. A curved frame composed of the connected cheeks $k k$ is attached to a portion of the periphery of each ratchet-wheel D by means of the metallic strap d , and these frames each carry a series of pawls, $c c$, in such positions that they are enabled to fall, one after another, into the teeth of their respective ratchet-wheels, as shown in Fig. 5. By means of the jointed bridle-rods $n n$ the pawl-frames $k k$ are connected to opposite ends of the rocker b , which is pivoted within the jaws of the strong supporter B . For the purpose of increasing the leverage I shall sometimes place a shorter rocker, a , immediately above the rocker b , and connect the ends of the former to the latter by means of suitable bridle-rods, $p p$.

Sockets $o o$ are formed in the ends of the rockers a and b for the reception of the hand-levers $A A$, which enable such reciprocating movements to be imparted to the pawl-frames $k k$ as shall impart an almost continuous motion to the windlass-shaft and chain-carriers whenever it may be desired to do so.

A cylindrical flange, which projects laterally from the periphery of each chain-carrier C , receives the strap-brake e , whose extremities are pivoted to the operating-lever f , as shown in Fig. 4.

A clearer must be employed with the Thomas Brown chain-carrier, for the purpose of raising the chain out of the radially-flanged annular groove of said carrier. In the construction of my improved chain-carrying windlass the aforesaid clearing function is performed by the tapering ends of the curved conveying-troughs J , which rest upon the barrels of the chain-carriers, while the outer ends of said troughs are fitted to and securely combined with the lower portions of the borders of the apertures in the main supporters E of the windlass-shaft. Consequently this arrangement enables a chain to be taken from either

hawse-hole directly to and beneath its appropriate chain-carrier, and then to be carried over the same and into the clearing and conveying trough J, which will pass the chain through the aperture in the aforesaid supporter E to the deck of the vessel, and at a point which may be in near proximity to the opening in the deck leading to one of the chain-lockers.

The bringing of the lifting strain to the under side of the chain-carrier, instead of the upper side of the same, as is the case with all other descriptions of windlasses, greatly reduces the strain upon the journal-supporters of my improved windlass, while it also enables the chain to be more easily lifted out of the radially-flanged groove of the same and conducted to the openings to the chain-lockers; and, furthermore, the said arrangement also enables the Thomas Brown underlifting chain-stoppers to be used in connection with my improved chain-carrying windlass. The said underlifting stoppers are so arranged that by raising the lever l to the position shown in Fig. 3 the friction-block m will be elevated to the position shown in Fig. 7, and when in that position the chain can glide freely over the curved jaws of the body of the stopper; and when the lever l is allowed to rest upon the deck of a vessel the friction-block m will be held in the position shown in Fig. 8, and when in that position it will enable the curved shoulders above and on each side of the same to stop and securely hold the chain.

My improved chain-carrying windlass may be constructed with one or with two chain-carriers, at the option of the builder.

Suitable pulley-heads, G G, may be placed upon the ends of the windlass-shaft for the purpose of enabling the windlass to operate upon ropes or cordage.

Having thus fully described my improved chain-carrying windlass, what I claim therein as new, and desire to secure by Letters Patent, is—

1. Placing the Thomas Brown chain-carrier C upon a windlass-shaft, and then combining therewith, and with either one of the windlass-supporters E, a curved clearing and conveying trough, J, in such a manner that the chain to be operated upon can be taken from the hawse-hole directly to and beneath the said chain-carrier, and then be carried over the same to and into the aforesaid clearing and conveying trough, substantially in the manner and for the purpose herein set forth.

2. When the Thomas Brown chain-carriers are placed upon a windlass-shaft, arranging them with ratchet-wheels and with a system of operating pawls and levers, substantially in the manner and for the purpose herein set forth.

3. Giving such a form and proportions to the Thomas Brown chain-carrier as shall enable a strap and lever-brake to be combined therewith, substantially as herein represented and described.

4. Mounting a Thomas Brown chain-carrier upon a windlass-shaft when the said chain-carrier is used in conjunction with the clearing and conveying trough J, and the Thomas Brown underlifting stopper, substantially in the manner herein set forth.

5. When the Thomas Brown chain-carriers are arranged with ratchet-wheels upon a windlass-shaft, the employment, in connection therewith, of the within-described arrangement of catches, which enables either of said chain-carriers to be coupled with or uncoupled from the windlass-shaft, substantially as herein set forth.

The above specification of my improved apparatus for working and stoppering chain cables signed this 2d day of May, 1862.

W. H. HARFIELD.

In presence of—

WILL DUFF,

Notary Public.

G. D. DUFF.

Notary Public, 5 Nicholas Lane, London.
